Houston, Tex., a corporation of Texas

Application July 27, 1950, Serial No. 176,212

9 Claims. (Cl. 20—57.5)

1

This invention relates to improvements in awning construction, and more particularly to awnings made from rigid material such as sheet aluminum.

Among the objects of the invention may be noted the provision of a durable, thoroughly practical and long-life metal awning; the provision of a metal awning which may be fabricated in a plurality of stock parts constructed and arranged so as to be readily assembled at the location of use; the provision of a metal awning which can be hung and taken down in exceedingly simple operations and with a minimum of effort; the provision of a metal awning which may be built up to the width dimension of a window or of double or triple windows, or of a porch, as required for a particular installation; the provision of a sectional metal awning whose sections may be simply and readily assembled at the location of use and which are so designed and constructed that they may be joined without sacrifice to the structural strength of the awning as a whole and in such manner that the joint between sections is not visible from the front side of the awning; the provision of a metal awning which is effectively weather-sealed along all joints, and more particularly the hinge joint between the hang bracket and the top edge of the awning face sheet, as well as between face sheet sections, the latter in case the awning is of the built-up or sectional type aforesaid; and the provision of a prefabricated metal awning characterized by inexpensive construction and by neat and attractive appearance.

The above and other objects and features of advantage of this invention will appear from the following detailed description, taken with the accompanying drawings, in which:

Fig. 1 is a front view of a metal awning of the invention illustratively of the size and type employed with a standard-width single window;

Fig. 2 is a side elevation thereof;

Fig. 3 is a perspective inside view of the awning illustrated in Figs. 1 and 2;

Fig. 4 is an enlarged section along line 4—4 of Fig. 3 illustrating the top edge construction of and the manner of hanging the awning;

Fig. 5 is a view similar to Fig. 3 but illustrating the built-up or sectional design by which the awning may be built up to the width of double or triple windows or to a relatively long length of porch;

Fig. 6 is a detail view illustrating the joint between face sheet sections as viewed from the inner side of the awning and further illustrating

2

typical intermediate bracing means employed for the greater width awnings; and

Fig. 7 is a part-sectional perspective view taken through the joint between sections as the latter is viewed from the front side of the awning.

Referring to the drawings, wherein like reference characters designate like parts throughout the several views, and particularly to Figs. 1—4 illustratively depicting an awning for installation on a single window of standard width constructed according to the principles of the invention, said awning comprises a face sheet 10 carrying a pair of top angles 11, 12 along its upper edge whose detailed construction and function will be later described; a stiffening angle 13 extending along its bottom edge which may be riveted to the inner side of the face sheet; ends 14, 15 provided with stiffening angles 16 along their bottom edges; and a hang bracket 17. Preferably, the face sheet 10 consists of a solid sheet of aluminum made up in widths of 28" to 52", in increments of 4", thus to fit all standard widths of single windows, the length of the sheet depending on the desired wall height and projections measurements of the particular installation. For extra strength, the face sheet 10 is provided with vertically extending narrow-width corrugations 18 spaced from one another across the width of the sheet, the corrugations being sunk into the body of the sheet and being concave outwardly, thus to form inward ribs on the under surface of the face sheet, and with a plurality of vertically extending small-depth crimps between each pair of said corrugations. The side edges of the face sheet are each formed with a depending flange 19, which is preferably edge-scalloped for ornamental effect. Similarly, the awning ends 14, 15 preferably consists of solid sheets of aluminum which are machine-cut to fit snugly under the scalloped edge flanges 19 of the face sheet, to which said ends are secured by screws 20, preferably in the installation of the awning. Like the face sheet, the ends 14, 15 are corrugated and crimped for strength, and additional ornamental effect may be imparted by edge-scalloping the bottom edges of both the face sheet and the awning ends, as indicated more particularly in Figs. 1 and 2.

The top angles 11, 12, which are desirably permanently affixed to the face sheet at the factory, and which extend along the top edge of the face sheet for its full width, are preferably constructed as illustrated in Fig. 4, the upper angle 11 of the pair having a horizontal body or web 55 portion 11a, a vertical flange 11b extending up-

wardly from one edge thereof, a sloped flange $11c$ extending downwardly from its other edge, said sloped flange terminating in an upwardly inclined edge flange $11d$ serving as a water deflecting gutter. The lower angle 12 comprises a horizontal body or web $12a$ of lesser width than the corresponding web portion $11a$ of the upper angle, said web having a vertical flange $12b$ extending upwardly from one edge, a vertical flange $12c$ extending downwardly from its other edge, and a sloped flange $12d$ extending downwardly from the lower edge of the vertical flange $12c$. The webs $11a$, $12a$ and their corresponding vertical flanges $11b$, $12b$ are secured in nesting or interfitting relation, so as to form a vertical L-shaped attaching portion but, by reason of the lesser width of the horizontal web $12a$ of the lower angle and the provision of its vertical depending flange $12c$, the sloped flanges $11c$, $12d$ are vertically spaced to provide an inclined, downwardly opening pocket which extends for the length of the angles, and in which is received the top edge portion of the face sheet 10 .

Preferably, the top edge portion of the face sheet is inserted into the aforesaid pocket to a depth such that the edge line of the underface ribs provided by the corrugations 18 engage against the depending vertical flange $12c$ of the lower angle 12 , the ribs thus supporting the face sheet proper raised from the sloped flange $12d$ of said angle. With the width of the pocket being substantially twice the overall thickness of the face sheet, it will be observed that the face sheet is also spaced from the sloped flange $11c$ of the upper angle 11 , and its upper terminal edge is moreover spaced slightly from the depending vertical flange $12c$ of the lower angle. This spacing permits air to circulate between face sheet and the top angles to which it is affixed and accordingly ventilation is provided along the top edge of the awning.

Securement of face sheet to the top angles 11 , 12 is preferably effected by a plurality of through bolts 22 extending between the sloped flanges $11c$, $12d$ of the latter and passing through the face sheet, each bolt mounting a pair of spacing bushings 23 , $23a$ which function to maintain the desired spacing between face sheet and sloped angle flanges.

The operations of hanging and taking down the awning are facilitated by a hang bracket 17 which extends the full width of the awning and whose construction is preferably that illustrated in Fig. 4. Said hang bracket is preferably of channel section and comprises a vertical web $25a$, an inclined lock flange $25b$ extending forwardly from its upper edge, and a horizontal supporting flange $25c$ extending forwardly from its lower edge, the latter flange projecting well beyond the edge line of the locking flange $25b$. The hang bracket is secured along the window facing above the top of the window in a preliminary operation as by attaching screws (not shown) passing through holes 26 in its vertical web and, once installed, can be left in place. The face sheet may be hung by the simple operation of holding it at an angular position above that shown in Fig. 4 and simultaneously projecting the L-shaped attaching flanges $11b$, $12b$ and their webs $11a$, $12a$ of the face sheet top angles into the channel of the hang bracket. By proper choice of the vertical height of said flanges $11b$, $12b$ of the top angles in relation to the space between the flanges $25b$, $25c$ of the hang bracket, lowering of the face sheet will result in the top edges of said flanges $11b$, $12b$ hooking beneath

the lock flange $25b$, and in the horizontal webs $11a$, $12a$ of the top angles engaging on and being supported by the horizontal lower flange $25c$ of the hang bracket. Such cooperation of the parts results in locking of the face sheet to the hang bracket and also provides the support required to maintain the face sheet at its proper projection angle. The reverse operation may be carried out in equally simple manner when it is desired to take down the awning for the winter season or in advance of a storm or other atmospheric condition making the same advisable.

Due to the impracticability of manufacturing, shipping and handling onepiece face sheets for the larger width awnings required for windows more than 52" wide, and for double or triple windows, as well as for porches of substantial length, it is desirable that the design of the awning be such that it can be built up from standard width parts to any width required for a particular installation. Such is achieved by the present invention partly by the face sheet construction aforesaid according to which the face sheets fabricated in standard one-window width may be employed as face sheet sections capable of assembly one with the other, or with a supplementary face sheet adapted to be interposed between adjacent sections, thus enabling the awning to be built up to desired width; and partly by a novel means for securing adjacent face sheet sections together, without sacrifice to the structural strength or appearance of the built-up awning as a whole. This feature of the invention will be explained in connection with Figs. 5-7 wherein it is assumed that the awning is to have total width corresponding to the width of two standard-width face sheets, of which one is designated 30 and the other 31 , joined along their adjacent or meeting edges.

As explained in connection with the single window awning illustrated in Figs. 1-4, each said face sheet is provided with depending side edge flanges 32 , 33 which may be scalloped as previously described in connection with the side edge flanges 19 of the face sheet 10 . At this point, it will be observed that in fabricating all face sheets, the side edge lines of each are spaced from the center lines of the adjacent edgemost corrugations 18 the distance of one-half the spacing between the other corrugations impressed in the face sheets. Accordingly, when the adjacent edges of two standard face sheets are brought together and joined, the edgemost adjacent corrugations of the joined face sheets are spaced from one another the same distance as the corrugations of each face sheet are spaced from one another.

With the above in mind, two face sections corresponding to those designated 30 and 31 in Fig. 5 may be brought together and their adjacent edge flanges 32 , 33 secured to one another by screws or bolts 34 in the manner illustrated in Fig. 6. Preferably, the joint between the sections is stiffened adjacent its bottom end by a joint angle 36 which may be bolted to the adjacent ends of the bottom angles 37 , 38 of the face sheet sections, which correspond to the bottom angle 13 shown in Fig. 3. The awning ends 39 , 40 , which correspond to those designated 14 , 15 (Fig. 3) are formed separate from the face sheet sections 30 , 31 and are attached as required in the installation operation.

To weather-seal the joint between the sections 30 , 31 and at the same time to render the joint invisible from the front side of the awn-

ing, the invention provides a weather-sealing and joint-masking member 42 which has length corresponding to the vertical length of the face sheet sections and is characterized by inverted U- or channel-section, with the width of the channel web 42a and the depth of its side flanges 42b, 42c corresponding to the spacing between any two adjacent corrugations of a face sheet section (and hence to the spacing between the adjacent edgemost corrugations of the joined sections) and the depth of the corrugations, respectively.

The weather-sealing member is of the same gauge and finish as the face sheet sections, and is assembled in the manner illustrated in Fig. 7, being secured to the face sheet sections as by screws or bolts 43. When so applied, said member not only covers and weather-seals the joint between the adjacent face sheet sections but also renders the joint invisible from the front side of the awning. Moreover, due to the interfitting relation of the side legs of the weather-sealing member in the concavities formed by the corrugations of the face sheet sections, the symmetrical design appearance of the awning as viewed from the outside thereof is preserved.

For the longer-width built-up awnings, some intermediate bracing is usually required, and this may be provided by an adjustable length awning brace 44, one end of which may be fastened to either of the bottom angles 37 or 38 and to the joint angle 36, if the brace is placed adjacent the joint, the other end of the brace being fastened to the window framing or building. In the event that the required width of awning cannot be provided by two standard-width face sheets, more than two face sheets whose total width makes up the required awning width may be joined in the manner explained above, and the awning may be braced at a suitable point or points along its width by braces corresponding to the brace 44 referred to above.

Without further analysis, it will be appreciated that an awning construction as described achieves the desirable objectives set forth in the foregoing, in that it may be fabricated complete at the factory in a plurality of stock parts capable of being readily shipped, and assembled at the location of use. Due to the unique construction of the face sheet top angles and the manner in which they cooperate with the hang bracket, a metal awning as aforesaid may be hung and taken down with a minimum of time and effort. A metal awning as described also lends itself to being built up to the width of double, triple or even larger windows, and of long porches, simply by the proper ordering of stock size parts which are capable of being joined to proper overall width in a thoroughly dependable and satisfactory manner. The invention also provides an extremely effective joint between sections by means which not only effect a thoroughly practical and durable weather-seal for the joint but also renders the joint invisible from the outer side of the awning.

As many changes could be made in carrying out the above constructions without departing from the scope of the invention, it is intended that all matter contained in the above description or shown in the accompanying drawings shall be interpreted as illustrative and not in a limiting sense.

We claim:

1. Metal awning construction including a rigid

metal face sheet, a pair of top angles extending the full width of the face sheet, the top edge of the face sheet being disposed between the lower flanges of said angles, means for securing said top edge to said flanges, the upper flanges of said angles interfitting one with the other to provide a vertically disposed L-shaped attaching portion, a channeled hang bracket extending the width of the awning and attachable to a building with its web disposed vertically and its flanges extending outwardly from the building, the upper flange of the bracket being inclined downwardly towards its bottom flange, said L-shaped attaching portion being insertible into the channel of the hang bracket for supporting engagement on the bottom flange thereof, and with its upper edge hooked under the inclined upper flange of said bracket.

2. Metal awning construction as set forth in claim 1, wherein the lower flanges of said top angles are sloped to correspond to the inclination of the face sheet and are vertically spaced from one another, and wherein the means for securing the top edge of the face sheet between the flanges effects spacing of said face sheet from said flanges.

3. Metal awning construction including a rigid metal face sheet, a pair of top angles extending the full width of the face sheet, said top angles each having a horizontal web portion and a vertical flange extending upwardly therefrom along its one edge and a downwardly inclined flange extending therefrom along its other edge, the web portions and the vertical flanges of said angles nesting one with the other to provide a vertically disposed L-shaped attaching portion, the downwardly inclined flanges of the angles being spaced vertically from one another to provide an elongated pocket, the top edge of the face sheet extending into said pocket, means for securing said top edge within the pocket, a channeled hang bracket extending the width of the awning and attachable to a building with its web disposed vertically and its flanges extending outwardly from the building, the upper flange of the bracket being inclined downwardly towards its bottom flange, said L-shaped attaching portion of the top angles being insertible into the channel of the hang bracket for supporting engagement on the bottom flange thereof, and with its upper edge hooked under the inclined upper flange of the bracket.

4. Metal awning construction as set forth in claim 3, wherein the inclined flanges of the top angles are spaced from one another a distance substantially greater than the thickness of the face sheet, and said face sheet securing means effects spacing of the secured top edge of the face sheet from both said inclined flanges.

5. Metal awning construction as set forth in claim 3, wherein the downwardly inclined flange of the lower top angle is connected to the web portion thereof by a vertical flange of appreciable height whereby the downwardly inclined flanges of said top angles are spaced substantially from one another, and wherein the securing means effects spacing of the secured top edge of the face sheet from both said downwardly inclined flanges.

6. Metal awning construction as set forth in claim 5, wherein the face sheet is provided with a plurality of under face ribs which engage against the downwardly inclined flange of the lower top angle, whereby the face sheet proper

is supported from said downwardly inclined flange but is raised therefrom.

7. In metal awning construction, a plurality of face sheets each carrying means along its top edge for hanging the same from a building and being provided along their adjacent side edges with depending vertical flanges, the face sheets being each provided with a plurality of narrow-width upwardly concave corrugations sunk into the body thereof and extending parallel to its flanged side edge, said corrugations being spaced equally from one another and the edgemost corrugation being spaced from the flanged side edge substantially one-half the distance between said corrugations, means for securing the edge flanges together thereby to join the face sheets, and means extending between the adjacent edgemost corrugations of the joined face sheets and overlying the joint between said face sheets both to weather-seal the joint and to mask the same from the front of the face sheets.

8. Metal awning construction as set forth in claim 7, wherein the weather-sealing and masking means comprises a U-member of the same material as the face sheets extending the length of the joint and whose legs extend into the concavities of the adjacent edgemost corrugations of the face sheets.

10
15
20
25

9. Metal awning construction as set forth in claim 7, wherein the weather-sealing and masking means comprises a U-member of the same material as the face sheets extending the length of said joint, said member having width corresponding to the spacing between the corrugations of the face sheet and side legs of depth corresponding to the depth of the corrugations, said member being disposed to bridge the joint and with its side legs seating in the adjacent edge-most corrugations of the joined face sheets.
